UNITED STATES PATENT OFFICE.

EDWARD ERICKSON, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

HEEL-BREASTING MACHINE.

1,084,259.

Specification of Letters Patent. Patented Jan. 13, 1914.

Application filed May 2, 1908. Serial No. 430,582.

To all whom it may concern:

Be it known that I, EDWARD ERICKSON, of Boston, in the county of Suffolk and State of Massachusetts, have invented certain new and useful Improvements in Heel-Breasting Machines, of which the following is a specification.

This invention relates to machines for trimming the breasts of shoe heels and has for its object to provide a machine for positively and accurately cutting the breast to the full depth of the heel, and for precluding the possibility of cutting beyond the heel and into the shank, regardless of whatever variations may exist in the thicknesses of heels and shanks of different shoes.

The undesirability of cutting into a shank ever so slightly is too well known to require explanation, and so it will be sufficient here to point out the means for and operation of breasting a heel according to the present invention.

Reference may be had to my co-pending application filed July 5, 1907, Serial No. 382,171, for the general character of a machine to which the present invention is applicable. This invention embodies, however, various improved mechanisms for accomplishing more effectively the same purpose as that to which the aforesaid application relates.

One of said improvements is a movable stop for positioning the work, and, as a result of making the stop movable, the effect is a decrease in the degree of movement necessary for advancing the work to the stop.

Another improvement is an increase of the radius of the work-supporting column which is adapted to oscillate to and from work-receiving position with a corresponding decrease of inclination.

Other improvements are described in the body of the specification, illustrated on the drawings and set forth in the claims.

On the drawings, forming a part of this specification,—Figure 1 is a front elevation of a machine constructed in accordance with this invention. Fig. 2 is a side elevation thereof. Fig. 3 is a front elevation in which the machine is in an operative state. Fig. 4 is a similar view showing the inoperative state. Fig. 5 is a vertical section on line 5—5 of Fig. 3. Figs. 6 and 7 are vertical cross sections on line 6—6 of Fig. 2, showing

different states of the means for controlling the driving mechanism. Fig. 8 is a perspective view of said controlling means. Fig. 9 is a section on line 9—9 of Fig. 2. Fig. 10 is an elevation of the brake. Fig. 11 is a section on line 11—11 of Fig. 2. Fig. 12 is a section on line 12—12 of Fig. 2. Fig. 13 is a fragmentary section on line 13—13 of Fig. 2. Fig. 14 is a fragmentary section on line 14—14 of Fig. 13. Fig. 15 is a section on the line 15—15 of Fig. 14. Fig. 16 is a fragmentary section on the line 16—16 of Fig. 14.

The same reference characters indicate the same parts wherever they occur.

The machine is mounted on a base 10. An upright standard or frame 11 is mounted on the base and supports a reciprocating head 12 movable in guides 13 and carrying a cutting knife 14. The head and knife overhang a work support 15 which is mounted on a jack or column 16 movable toward and from the knife 14, and to and from the path of the same.

The head 12 is provided with an adjusting rod 17 and screw 18, of which the former is pivotally connected to one end of a link 19, see Figs. 2 and 12. The other end of the link is connected with a crank 21 on one end of a driving shaft 20. The shaft carries a loose pulley 22 and clutch mechanism by which it is made to rotate the shaft. Clutch-controlling mechanism is provided for causing the clutch to impart a single revolution at a time to the shaft as hereinafter explained. By this means, the knife 14 is given a movement toward and from the work, whereupon it stops until subsequently set in motion again by the clutch-controlling mechanism.

The work-supporting column 16 is made in two sections and is provided with adjusting mechanism by reason of which it is extensible. The lower section is provided with a head 23 embracing a nut 24 and carrying a pin 25. The upper section is provided with a screw-threaded end which extends through the nut 24 and into the head. It is also provided with a collar 26 which embraces the pin 25 and so prevents the upper section from turning in the head 23. The upper section may be raised or lowered by means of the nut, for the purpose of obtaining an adjustment of the upper section. The

lower section of the column 16 is mounted so as to slide endwise in an oscillatory guide or fulcrum member 27, which is attached to the standard 11 as shown in Figs. 2 and 5. A cylindrical boss 28 formed on the member 27 sets into a fixed plate 29 and is fastened therein so as to be free to turn. A pin 30, affixed to the member 27, engages a collar 31 affixed to the column 16 and so prevents axial rotation thereof. The column is adapted to be raised and lowered in the member 27 by means of toggle levers 32 of which one is pivotally connected to the collar 31 and the other to a fixture 33 on the base 10. The levers 32 are jointed together by a pin 34 to which is attached one member 35 of an extensible link. The other members of the link are a member 36 which is adapted to telescope with the member 35, and two helical springs 37 which tend to draw together the members 35 and 36. The member 36 is pivotally connected to the free end of an arm 38 affixed upon a rock-shaft 39 mounted in bearings on the base 10. A treadle 40 is affixed to the rock-shaft, by means of which the toggle levers 32 may be actuated to raise or lower the column 16. As shown by Fig. 1, the column is depressed, but as shown by Fig. 3, it is elevated by the toggle whose pivots stand in alinement parallel to the path of the column. In the latter figure, the extensible link is extended, for a purpose hereinafter explained, and the springs 37 are exerting their tension upon the joint of the toggle which, however, cannot pass beyond the alined position because of the engagement of opposing shoulders 41 with which they are provided. By means of the toggles and the extensible link, the work is moved to operative position by yielding pressure which increases and finally ceases when the toggles and the column become rigidly related as the work reaches operative position.

In order to insure a correct position of the work prior to operation of the knife, the machine is provided with a stop or gage 42 which is adapted to be engaged by the shank of a shoe when the latter is moved to operative position, as shown by Fig. 3. The gage is an arm affixed to the upper end of an upright rock-shaft 43 mounted in fixed bearings on the standard 11, and may be moved transversely in relation to the parallel movements of the knife and work-support. The lower end of the rock-shaft 43 is provided with a forked lever 44 which embraces an actuating member 45 affixed to the lower section of the column 16. By reason of mounting the column in the oscillatory member 27, as hereinbefore described, they are adapted to be rocked upon the boss 28 to either of the positions shown by Figs. 1 and 4, and, when so rocked, the actuating member 45 rocks the shaft 43 thus imparting lateral

movement to the stop 42. The reason for moving the stop is explained in the following description of the operation of the jack.

Referring now to Fig. 4, it appears that the jack is inclined to a position for receiving a shoe, and that the stop or gage 42 is in an inoperative position. See also dotted lines of Fig. 13. After a shoe is placed over the work support as shown, the jack may be manually rocked to an upright position as shown by Fig. 1, the jack meanwhile occupying its lower position. As it approaches an upright position, it imparts movement to the stop 42 which swings outwardly over the shoe in the path of, but following, the heel. When in the position shown in Fig. 1, the stop extends over the shank of the shoe, not touching it but below the plane of the heel tread. From this position the shoe is raised to operative position by depressing the treadle 40 so as to draw the toggle levers into alinement, as shown by Fig. 3. This elevates the column 16 so that the shank of the shoe is pressed against the stop, and the heel is moved into engagement with another gage indicated at 46. See Figs. 14 and 15. The gage 46 has a two-fold purpose, of which one is to serve as means for gaging the position of the shoe as it approaches the stop 42. The other purpose is to bind the shoe firmly upon the work support to prevent it from twisting. For this purpose it is made to yield and is furthermore made adjustable as to inclination, and so also is the work support 15.

The support 15 is pivotally mounted on a head 47 which is affixed to the upper end of the column 16. An adjusting screw 48 threaded into the head serves as means for adjusting the inclination of the support and supporting it in any position.

The gage 46 is adapted to be adjusted to conform to the inclination of the work support and for this purpose is pivoted at 49 to a carrier 50. The carrier has a plunger 51 which extends through a bracket 52 attached to the standard 11, and an adjusting screw 53 which determines the inclination of the gage. The latter is held by a spring 54 against its screw 53, and the carrier as a whole is depressed by a helical spring 55 contained in the bracket 52. Stop nuts 56 on the end of the plunger 51 limit its downward movement.

Referring now again to the extensible link which actuates the toggle levers 32, it will be remembered that the former, after moving the toggles into alined position, is capable of extending, and the latter is for the purpose of permitting further downward movement of the treadle 40. The purpose of this additional movement is to actuate the clutch-controlling mechanism which sets the knife 14 in motion. The latter may be briefly described, although it is not an essential part 130

of the present invention. A detailed description of the controlling mechanism may be found in the application filed January 11, 1907, by H. A. Ballard, Serial No. 351,814.

5. In addition to the shaft 20 having the loose driving pulley 22, the clutch mechanism comprises co-operative cone-clutch members 60 and 61, the former formed with or attached to the pulley and the latter splined upon the shaft. The clutch members are 10 normally separated by a spring 62 interposed between their tubs, which forces the pulley member against a screw-threaded collar 63, and the cone member 61 against a transversely movable wedge member 64 of the controller mechanism.

65 is a complementary wedge member pinned or otherwise affixed upon the shaft, which carries the wedge member 64 and 20 which has a cylindrical hub on which an annular controller 66 is adapted to move parallel to the axis of the shaft. A spring 67 interposed between opposed faces of the two wedge members normally holds the member 25 64 in operative position for compressing the clutch members 60 and 61. The controller 66 is straddled by a yoke or shipper 68, pivoted at 69 to a stationary support, and is normally held by a spring 70 in operative position, 30 that is, the position which renders inoperative the normally operative wedge members. These relations can be seen in Fig. 5 in which the controller 66 is disengaged from the member 64. The latter is therefore in its normally operative position, and consequently the clutch members are rendered operative although, when in their normal position, they are inoperative. The shipper 68 is connected to a 40 rock arm 71 by a toggle or spreader 72 which has a universal ball joint at each end. A spring 73 connected to the arm 71 tends to move the latter to the left, as shown by Fig. 8, in harmony with the tendency of the 45 spring 70.

The arm 71 has a pin or lug 74 which is adapted to support the free end of a swinging hooked latch 75 pivotally connected to an arm 76 formed upon the treadle 40. The 50 latch 75 has a square face 77 and a curved face 78, the former adapted to engage the lug 74, and the latter adapted to engage a roller 79 mounted on a fixed support. The latter instrumentalities constitute a tripping mechanism by which the treadle 40 is made 55 to set the clutch mechanism as follows: Fig. 8 shows the clutch-controlling mechanism in the position corresponding to the lower position of the jack, as shown by Fig. 1. When 60 the treadle 40 is depressed, it elevates the work to operative position as hereinbefore described, and incidentally it moves the arm 76 and latch 75 from the position shown by Fig. 8 to the right. That portion of the 65 movement of the treadle which alines the

toggles 32 causes the square face 77 to approach the lug 74, and further movement of the treadle, as permitted by the aforesaid extensible link, causes the face 77 to engage and move the lug 74 thereby rocking the arm 71. By this means the shipper is actuated so as to disengage the controller 66 from the member 64 and permit engagement of the clutch members. Driving connection is thereby established between the pulley 22 and the shaft 20, but meanwhile the curved face 78 of the latch engages the roller 79 and is thereby raised so that the square face 74 is disengaged from the lug 74. The spring 73 then returns the arm 71 and the spring 70 returns the shipper 68 to their normal positions.

The controller (see Fig. 9) has a flat face 80 which, as the wedge members rotate, moves in under a block 81 affixed to the member 64. The block therefore rides upon the said face and is moved transversely against the tension of the spring 67, thereby rendering the wedge member and the clutch members inoperative. The block 81 also 90 has an eccentric outer face which engages a roll 82 in the free end of a brake lever 83. The lever is fulcrumed at 84 to one end of a brake band 85 which surrounds a flange 86 on the clutch member 61. The 95 other end of the band is connected by a pivoted link 87 with the lever 83, and by this means the ends of the band are drawn together when the arm is actuated by the block 81. Diametrically opposite the link 87 the 100 band is supported and prevented from revolving by a bracket 88 affixed to the upright standard.

The effect of the described clutch and controlling mechanism is to impart a single 105 revolution to the shaft 20 and then automatically stop it by means of the brake each time the treadle is depressed. A revolution of the shaft effects a movement of the knife toward and from the work. In practice 110 the knife is so adjusted as to advance to the transverse plane of the work-engaging face of the stop 42, and so it follows that, if the shank of a shoe is in contact with the stop, the knife is capable of advancing to but not 115 into the shank. A convenient means for adjusting the range of movement of the knife is shown in detail in Figs. 2 and 13, and comprises a worm 90 intermeshing with teeth on the periphery of the nut 18, a shaft 120 91 carrying the worm, and a hand wheel 92 on the shaft.

The object of moving the stop 42, when the work support is moved laterally, is to decrease the extent of movement of the 125 column toward and from the knife necessary for permitting lateral movement of the work support to and from work-receiving position. For example, suppose the stop were immovable and that the shoe is in 130

operative position as in Fig. 3. In order to move the work support to the position shown by Fig. 4, it would be necessary to depress it slightly more than the depth of 5 the heel in order to make it possible for the heel to pass laterally under the stop. But, according to the present invention, it is not necessary to depress the tread of the heel below the plane of the stop in order to 10 enable the work support to move laterally. In the present instance, it is necessary to depress the work support only so far as to disengage the shank of the shoe from the stop, when the work support may be moved 15 laterally because the stop likewise moves laterally in the same transverse plane as the heel. In the reverse operation, the heel and the stop approach operative position in the same transverse plane. The advantage 20 of thus reducing the necessary range of movement of the work toward and from the knife is to minimize the degree of movement necessary in the actuating means, namely the toggle levers, and consequently 25 the manual power required is of a minimum degree. There is also an advantage gained by mounting and actuating the work-supporting column in the aforesaid manner. The column, by reason of its pivotal bearing 30 member, when moved laterally moves in an arc whose radius is so long that inclination of the column is so slight as to be unobjectionable in applying and removing the work. The increase in the radius is made 35 possible by locating the axis below the point at which the elevating means is connected to the column.

Having thus explained the nature of my 40 said invention, and described a way of constructing and using the same, although without attempting to set forth all of the forms in which it may be made or all of the modes of its use, what I claim is:—

1. A heel breasting machine, comprising a 45 cutting knife, a work support movable toward and from the knife, and a stop movable with relation to the knife for limiting the movement of the work toward the knife, said stop being fixed as to movement in line 50 with the work and knife.

2. A heel breasting machine, comprising a 55 cutting knife, a work support movable toward and from the knife, and a stop movable to and from the path of the work for arresting the movement of the work toward the knife and for engaging the work throughout the operation of the knife.

3. A heel breasting machine comprising a 60 breasting knife, means for imparting cutting movement thereto, a work support movable toward the knife in the direction opposed to that of the knife's cutting movement, and a gage for arresting the work to determine the depth of the cut, said gage 65 being movable transversely of the aforesaid

movements to and from work-engaging position.

4. A heel breasting machine, comprising a cutting knife, a work support movable toward and from the knife, and a movable 70 stop for arresting movement of the work toward the knife, said stop being movable transversely of the work support, but otherwise fixed.

5. A heel breasting machine, comprising a cutting knife, a work support movable to and from alinement with the knife, and movable toward and from the knife in alinement therewith, and a movable stop for arresting movement of the work toward the 80 knife, said stop being movable with relation to the knife and work support to and from the path of the work transversely of said path.

6. A heel breasting machine, comprising a cutting knife, a work support movable toward and from the knife and movable transversely to and from alinement with the knife, a movable work-engaging stop adapted to arrest movement of the work toward the knife, and means for moving the stop transversely of said alinement to and from 90 work-engaging position.

7. A heel breasting machine, comprising a cutting knife, a work support movable toward and from the knife and movable transversely to and from alinement with the knife, a movable work-engaging stop for arresting movement of the work toward the knife, and means connecting the work support and the stop for moving the stop to and from work-engaging position when the support is moved to and from alinement with the knife.

8. A heel breasting machine, comprising a cutting knife, a work support movable toward and from the knife and movable transversely to and from alinement with the knife, a transversely movable work-engaging stop for arresting movement of the 105 work toward the knife, and means adapted to be actuated by transverse movement of the support for moving the stop to or from work-engaging position.

9. A heel breasting machine, comprising a movable knife, continuously moving, normally inoperative, driving means for moving said knife, a work support, an oscillatory column for said support adapted to be reciprocated transversely of its axis of oscillation, rigidly supported toggle levers for reciprocating the column, controlling means for rendering said driving means operative, and manually operative means for alining said toggle levers and actuating said controlling means in the order given.

10. A heel breasting machine, comprising a knife, a work support, said knife and work support being movable in alinement toward and from each other, means for mov-

ing the knife toward and from the work support, disconnectible driving mechanism for said knife-moving means, said mechanism being adapted to normally become disconnected, means for moving said work support toward the knife and for holding it positively against retrograde movement, controlling means for causing driving connection of said driving mechanism, and manually operative means for first actuating said work-support means, and then said controlling means, whereby the work is first placed in operative position and then the knife is actuated.

11. A heel breasting machine comprising a knife and work support movable toward and from each other, said work support being otherwise movable to and from alinement with the knife, and a stop movable transversely of the line in which said knife and support move toward and from each other, and adapted to limit movement of the work toward the knife.

12. A heel breasting machine comprising a reciprocatory knife, knife-operating mechanism, a work support movable transversely of the direction of movement of said knife

to bring the work into alinement with the knife and movable in the direction of movement of the knife to bring the work in position to be cut, and a gage fixed in the direction of movement of the knife but movable transversely of said direction of movement of said knife to arrest the work in its movement toward the knife.

13. A heel breasting machine comprising a reciprocatory knife, knife-operating mechanism, a work support movable transversely of the direction of movement of said knife to bring the work into alinement with the knife and movable in the direction of movement of the knife to bring the work in position to be cut, a gage movable transversely of said direction of movement of said knife to arrest the work in its movement toward the knife, and operative connections between said support and said gage in consequence of which one is actuated by the other.

In testimony whereof I have affixed my signature, in presence of two witnesses.

EDWARD ERICKSON.
